FIG. 1 is a front perspective view of a table according to our new design;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a third side view thereof;

FIG. 8 is a fourth side view thereof; and,

FIG. 9 is a top view thereof.
